(57) **CLAIM**

The ornamental design for an electrical outlet and light switch cover, as shown and described.

DESCRIPTION

FIG. 1 is an upper perspective view of an electrical outlet and light switch cover showing my new design.

FIG. 2 is a front view of an electrical outlet and light switch cover showing my new design.

FIG. 3 is a rear view of an electrical outlet and light switch cover showing my new design.

FIG. 4 is a bottom end view of an electrical outlet and light switch cover showing my new design.

FIG. 5 is a top end view of an electrical outlet and light switch cover showing my new design.

FIG. 6 is a left side view of an electrical outlet and light switch cover showing my new design.

FIG. 7 is a right side view of an electrical outlet and light switch cover showing my new design.

FIG. 8 is an upper perspective view of a first alternative embodiment of an electrical outlet and light switch cover showing my new design.

FIG. 9 is a front view of a first alternative embodiment of an electrical outlet and light switch cover showing my new design.

FIG. 10 is a rear view of a first alternative embodiment of an electrical outlet and light switch cover showing my new design.

FIG. 11 is a bottom end view of a first alternative embodiment of an electrical outlet and light switch cover showing my new design.

FIG. 12 is a top end view of a first alternative embodiment of an electrical outlet and light switch cover showing my new design.

FIG. 13 is a left side view of a first alternative embodiment of an electrical outlet and light switch cover showing my new design.

FIG. 14 is a right side view of a first alternative embodiment of an electrical outlet and light switch cover showing my new design.

FIG. 15 is an upper perspective view of a second alternative embodiment of an electrical outlet and light switch cover showing my new design.

FIG. 16 is a front view of a second alternative embodiment of an electrical outlet and light switch cover showing my new design.

FIG. 17 is a rear view of a second alternative embodiment of an electrical outlet and light switch cover showing my new design.

FIG. 18 is a bottom end view of a second alternative embodiment of an electrical outlet and light switch cover showing my new design.

FIG. 19 is a top end view of a second alternative embodiment of an electrical outlet and light switch cover showing my new design.

FIG. 20 is a left side view of a second alternative embodiment of an electrical outlet and light switch cover showing my new design.

FIG. 21 is a right side view of a second alternative embodiment of an electrical outlet and light switch cover showing my new design.

FIG. 22 is an upper perspective view of a third alternative embodiment of an electrical outlet and light switch cover showing my new design.

FIG. 23 is a front view of a third alternative embodiment of an electrical outlet and light switch cover showing my new design.

FIG. 24 is a rear view of a third alternative embodiment of an electrical outlet and light switch cover showing my new design.

FIG. 25 is a bottom end view of a third alternative embodiment of an electrical outlet and light switch cover showing my new design.

FIG. 26 is a top end view of a third alternative embodiment of an electrical outlet and light switch cover showing my new design.

FIG. 27 is a left side view of a third alternative embodiment of an electrical outlet and light switch cover showing my new design; and,

FIG. 28 is a right side view of a third alternative embodiment of an electrical outlet and light switch cover showing my new design.

Any shading and cross-hatching are not features of the design but are utilized to illustrate the surface contours of the electrical outlet and light switch cover in the drawings.
